(57) **CLAIM**

The ornamental design for a vaping device, as shown and described.

DESCRIPTION

FIG. 1 is a perspective view of a first embodiment of a vaping device showing my new design.

FIG. 2 is a front view of FIG. 1.

FIG. 3 is a back view of FIG. 1.

FIG. 4 is a left side view of FIG. 1.

FIG. 5 is a right side view of FIG. 1.

FIG. 6 is a top view of FIG. 1.

FIG. 7 is a bottom view of FIG. 1.

FIG. 8 is a perspective view of a second embodiment of a vaping device.

FIG. 9 is a front view of FIG. 8.

FIG. 10 is a back view of FIG. 8.

FIG. 11 is a left side view of FIG. 8.

FIG. 12 is a right side view of FIG. 8.

FIG. 13 is a top view of FIG. 8.

FIG. 14 is a bottom view of FIG. 8.

FIG. 15 is a perspective view of a third embodiment a vaping device.

FIG. 16 is a front view of FIG. 15.

FIG. 17 is a back view of FIG. 15.

FIG. 18 is a left side view of FIG. 15.

FIG. 19 is a right side view of FIG. 15.

FIG. 20 is a top view of FIG. 15; and,

FIG. 21 is a bottom view of FIG. 15.

The broken lines in the drawings depict portion of the vaping device that form no part of the design.

1 Claim, 9 Drawing Sheets
